Mr Hauseby

Dec. 1820

Elias Ingraham, of Bristol, Conn.

Letters Patent No 1820-Dated Sept 29, 1868

Design for a Clock Case.

The schedule referred to in these Letters Patent and making part of the same.

To all whom it may concern:

Be it known that I, Elias Ingraham, of Bristol, County of Hartford and State of Connecticut, have invented or produced a new and original design for a clock front, and I do hereby declare that the following is a full and exact description of the same, referring to the photographic views, in which the same letters indicate like parts.

In the accompanying photographic views is shown a new and original design for a clock front. It is the base of the case. It has square edge sides, connected by a circular square edge top C, and resting upon the base B, and ornamented with half-columns D, and a half circle head E. F and G, are plain moulded sashes. H, are rosettes, all combined to produce a plain ornamental design for a clock front.

What I claim, therefore, and desire to secure by Letters Patent is the design for a clock front as herein represented and described.
